UNITED STATES PATENT OFFICE.

VICKTOR ROSENLOF, OF TIMBER LAKE, SOUTH DAKOTA.

STRAP CONNECTION FOR HARNESS.

1,376,781.

Specification of Letters Patent.

Patented May 3, 1921.

Application filed October 27, 1916. Serial No. 128,055.

To all whom it may concern:

Be it known that I, VICKTOR ROSENLOF, a citizen of the United States of America, and resident of Timber Lake, in the county 5 of Dewey and State of South Dakota, have invented certain new and useful Improvements in Strap Connections for Harness, of which the following is a specification.

This invention relates to harness and particularly to means for adjusting traces, the 10 connections between the collars of harness and the whiffletrees, the said invention also including means by which the back bands and the belly bands of harness are connected, so that the traces are supported at 15 the sides of the animal to which the harness is applied.

A further object of this invention is to produce a connection of the character indicated which will permit ready adjustment 20 of the parts to insure automatic clamping to hold the parts in adjusted positions, the said invention also having the advantage that it is of comparatively simple construction, proving at the same time inexpensive 25 to manufacture.

With the foregoing and other objects in view, the invention consists in the details of construction, and in the arrangement and 30 combination of parts to be hereinafter more fully set forth and claimed.

In describing the invention in detail, reference will be had to the accompanying drawings forming part of this specification, 35 wherein like characters denote corresponding parts in the several views and in which—

Figure 1 illustrates a view in perspective showing the application of the invention to 40 harness;

Fig. 2 illustrates a perspective view of fragments of the harness with the invention applied thereto;

Fig. 3 illustrates a sectional view on the 45 line *a—a* of Fig. 4; and

Fig. 4 illustrates a plan view of the device.

In these drawings 5 denotes the staple or bracket for attachment to the hames of a 50 harness, 6 a flexible member extending from the said bracket 5 and adapted to be adjustably connected to the coupling 7, which coupling is a framelike structure having loops 8 and 9 at its sides for attachment of 55 the back band 10 and belly band 11 respectively. The coupling 7 has an aperture 12

which, with the frame, constitutes a means by which the trace or tug 13 is attached to the said coupling and can be made adjustable therein by reason of the fact that it can 60 be curved around the bar and the loose end extended parallel with the trace or tug and held in place.

The frame of the coupling also has ears 14 and 15 in which a clamping rod 16 is pivoted eccentrically and the surface of the 65 said clamping bar is knurled or otherwise roughened to insure proper frictional contact with the flexible member 6 so that the said flexible member 6 may be adjustably 70 held in place by the said coupling. It is shown in the drawing that the clamping bar acts in conjunction with a cross bar 16^a which comprises a part of the frame.

A device made in accordance with this 75 invention may have its body stamped from metal or it may be cast and the parts associated therewith may be readily assembled so that the cost of production is relatively small and as a means for making harness 80 adaptable to animals of different sizes, and has advantages which will be apparent to those skilled in the art and since the clamping bar is eccentrically mounted, it immediately engages and clamps the member 6 85 and clamping action is augmented in proportion to the pull on the said flexible member.

A tongue A has an eye B which is mounted on a pivot C of the body and the curve 90 of the tongue is such as to cause the said tongue to frictionally engage a strap which may be inserted under it so as to hold the strap by reason of its frictional engagement.

I claim—

In a harness buckle, a frame longitudinally curved, a plurality of lips extending outwardly therefrom, bars journaled therein, one of said bars being journaled eccentrically and having a roughened surface 100 adapted to automatically grip a strap when said strap is pulled in one direction, a bar extending across said frame parallel with said eccentric bar forming a base with which the eccentrically mounted bar coacts, a 105 tongue having a curved surface for engaging a strap, said curved tongue terminating in an eye, said eye being pivotally mounted on one of said first mentioned bars, as and for the purpose described.

VICKTOR ROSENLOF.
